UNITED STATES PATENT OFFICE.

FRANK W. WALLACE, OF CHATTANOOGA, TENNESSEE, ASSIGNOR OF ONE-HALF TO
WILLIAM G. OEHMIG, OF CHATTANOOGA, TENNESSEE.

VIBRATORY MIXER.

Application filed August 30, 1926. Serial No. 132,517.

The invention aims to provide a simple and inexpensive, yet an efficient and desirable device for use by druggists, pharmacists, physicians, dentists and others to produce 5 perfect blending of two or more powders or other dry substances.

The substances to be mixed or blended are preferably placed in a glass bottle and the latter is corked, and it is a further object of 10 the invention to provide a new and improved clamp construction for holding the bottle or in fact any analogous container which may be used, in proper position upon the vibratory member of the device, so that when 15 said member is vibrated, similar movement will be imparted to the container, causing thorough agitation and mixture of its contents.

With the foregoing in view, the invention 20 resides in the novel subject matter herein-after described and claimed, the description being supplemented by the accompanying drawing.

Fig. 1 is a perspective view of the device 25 partly separated.

Fig. 2 is a longitudinal sectional view through the upper end of the device showing a container held therein.

Fig. 3 is a vertical transverse section sub-30 stantially through the central portion of Fig. 2.

In the form of construction selected for 35 illustration, 10 designates an arm formed of resilient metal and provided with any desired means at one end for securing it to a support, such as a counter. In the present showing, this end of the arm 10 is provided with a base 11 having openings 12 to receive attaching fasteners. The free end of the arm 40 10 carries a clamp 13 for a container 14, in which the substances to be mixed or blended, are placed, this container being preferably in the form of a glass bottle having one end provided with a cork 15.

In the preferred form of construction, the 45 clamp 13 includes two metal base plates 16 and 17 of elongated form and slidably connected with each other. In establishing this 50 sliding connection any desired construction may be employed, but I prefer to provide the plate 16 with inturned flanges 18 which 55 slidably overhang and extend along the edges of the plate 17. One of these plates, the plate 16 in the present instance, is secured in any appropriate manner to the up-

per or free end of the arm 10, and it may here be explained that while I prefer to use the device with this arm in an upright position, this is not essential. Preferably, a nut 19 is soldered or otherwise secured to the 60 plate 16 and the free end of the arm 10 is threaded tightly into this nut to connect said plate and arm.

The outer ends of the plates 16 and 17 are 65 provided with jaws 19 and 20 which may well be formed by laterally bending said ends of the plates. These jaws are adapted to engage the ends of the container when the plates 16 and 17 are moved inwardly with respect to each other after positioning said 70 container upon them. Then, the plates and jaws are held against separation, by a longitudinally elastic member which is attached at one end to one of the jaws and has a detachable connection at its other end with the other of said jaws. In the construction herein disclosed, this elastic member consists of a coiled tension spring 21, a stem 22 secured to one end of this spring and a knob 23 secured to the outer end of said stem, said 75 knob preferably having a hub which provides a shoulder 24 at the outer portion of the stem. This stem is received in a notch 25 formed in a portion of the jaw 20, said portion being here shown in the form of a 80 separate metal plate 26 which is soldered or otherwise secured to said jaw.

The end of the spring 21, remote from the 85 knob 23, is in the present disclosure, connected with a loop 27 on a length of wire 28, 90 said length of wire being bent between its ends into U-shape to provide said loop and having its end portions 29 bent into angular form and projected inwardly beyond the body portion of the jaw 19, to straddle 95 the container 14 and prevent lateral movement of the latter from the space between the plates 16-17 and the elastic member 21-22-23. It will thus be seen that the 100 container is effectively held in position within the clamp 13, it being of course understood that the spring 21 must be stretched before the stem 22 can enter the notch 25, and that after such stretching and the entrance of said stem into the notch, the tension of said spring will cause the shoulder 24 to engage the outer side of the plate 26. Thus, the spring exerts an inward pull on the jaws and plates so as to tightly hold the 105 former in contact with the ends of the con- 110

tainer. When the substances within the container have been thoroughly mixed, it is only necessary to disengage the knob and stem 23—22, from the plate 26. This permits outward sliding of the plate 17 upon the plate 16, releasing the jaws 19 and 20 from contact with the container and permitting easy removal of the latter. Then, another container may be inserted if desired. Obviously, the device is adjustable according to the length of the container, or the distance which the cork 15 may protrude therefrom.

After clamping the container in place, the clamp may be moved laterally by hand, preferably by pulling upon a knob 30 provided for that purpose. This laterally springs the arm 10, so that when the knob is released, said arm will vibrate, thus similarly vibrating the clamp 15, the container and the contents of the latter, insuring thorough blending of such contents.

The invention is simple and inexpensive and may be very advantageously used for not only efficiently but quickly mixing powders or other substances. The details disclosed may be followed if desired, but within the scope of the invention as claimed, numerous variations may be made.

30 I claim:—

1. In a vibratory mixer, a container clamp comprising two elongated base plates one of which has on its side edges inwardly turned flanges to slidably receive the other plate, said plates having their outer ends bent laterally to form clamping jaws, a notched plate projecting from one of said jaws, a coiled spring secured at one end to one of said jaws, a stem secured to the opposite end of said spring and adapted to be engaged with said notched plate when the spring is stretched to draw said base plates together and the jaws thereon into engagement with the ends of a container resting on said base plates whereby the container is held in position between said jaws and a knob on the end of said stem to bear against said notched plate thereby holding said spring in stretched position for engaging the jaws with the container.

2. In a vibratory mixer, a container clamp comprising an elongated portion to extend longitudinally at one side of the container,

relatively movable jaws projecting from said elongated portion to engage the ends of the container, an elastic member connected to one of said jaws and adapted to be stretched to the other jaw and extending longitudinally along the side of the container opposite said elongated portion, and means for releasably connecting said elastic member to said other jaw, whereby said member will inwardly pull upon the jaws to effect clamping of the container between them.

3. In a vibratory mixer, a container clamp comprising two slidably connected plates extending longitudinally along one side of the container and having laterally projecting jaws at their outer ends to engage the ends of the container, and spring means for inwardly sliding said plates upon each other to hold the jaws engaged with the container, said means extending longitudinally along the opposite side of the container.

4. In a vibratory mixer, a container clamp comprising two slidably connected plates having laterally projecting jaws at their outer ends to engage the ends of the container, a longitudinally elastic jaw-holding member connected to one of said jaws and adapted to be stretched to the other jaw, and means for detachably connecting said elastic member with said other jaw, said member and plates being in spaced parallel relation to extend along opposite sides of the container.

5. A structure as specified in claim 2: said means for releasably connecting said elastic member with said other jaw comprising a notch in the latter to receive a portion of said member and a shoulder on the latter to engage the jaw and hold the member under tension.

6. A structure as specified in claim 2: said connection between said elastic member and said one jaw including a length of wire secured to said jaw, said wire having a V-shaped intermediate portion to which said member is connected, and angular end portions which project from said one jaw toward the other jaw to straddle the container.

In testimony whereof I have hereunto affixed my signature.

FRANK W. WALLACE.
